CLARENCE K. SUYDAM, OF UTICA, NEW YORK, ASSIGNOR OF FOUR-TENTHS TO LOUIS W. STONE, OF UTICA, NEW YORK.

SHUTTLE.

1,409,793.

Specification of Letters Patent. Patented Mar. 14, 1922.

Application filed July 8, 1918. Serial No. 243,783.

To all whom it may concern:

Be it known that I, CLARENCE K. SUYDAM, a citizen of the United States, and a resident of Utica, in the county of Oneida and State of New York, have invented certain new and useful Improvements in Shuttles; and I do hereby declare that the following is a full, clear, and exact description thereof, which will enable others skilled in the art to which it appertains to make and use the same, reference being had to the accompanying drawings, and to the reference numerals marked thereon, which form part of this specification.

15 My present invention relates to loom shuttles.

The purpose of this invention is to provide an improved loom shuttle and one which is simple and economical in construction and very durable and efficient in operation.

Loom shuttles are almost universally constructed of wood. This is the most practical material to form the shuttle from and is found by long experience to be practically the only material that will give the proper contact or friction between the shuttle and the binders and the backs of the shuttle boxes to hold the shuttle from rebounding from the shuttle boxes. On the other hand the wood is a constant source of trouble in the shuttle in that the slope or curve at both ends of the shuttle where the shuttle tapers from full size to the metal tip necessarily cuts across the grain of the wood. This nose or slanting portion of the shuttle at the same time is the very portion which is brought into contact with the warp of the loom under considerable tension. Under these circumstances the shuttle sooner or later wears rough through the action of the warp engaging the ends of the fiber of the wood. As soon as the shuttle has even slightly roughened it needs to be smoothed down by whittling or sandpapering and this process has to be continued as often as the shuttle wears rough. If the shuttle is not thus taken care of as soon as a small part of the shuttle has worn rough it will catch more positively in the warp and brush up a larger splinter of wood in the shuttle and often break a number of threads of the warp. The brushing up of the deep splinter requires the shuttle to be trimmed down just

use entirely. The breaking of the ends of warp makes a noticeable defect in the cloth resulting in a great waste of material and time. This roughening of the shuttles occurs mostly on the top of the shuttle where the tension of the warp against the shuttle is more pronounced, although there is a little tendency for the bottom of the shuttle to roughen. The sides of the shuttle are not subject to being roughened in this way and practically receive no wear from their contact with the binders. This roughening or splintering of the top of the shuttle is a constant source of trouble in the operation of the loom and is the element that limits the life of the shuttle.

The above mentioned tendency of shuttles to splinter or roughen has made it necessary to form the shuttles from only the most close grained wood. In practice shuttles are made only from dog wood as no other wood resists the tendency to roughen for a sufficient time to make it worth while to make shuttles of other woods.

The main purpose of my invention is to provide a loom shuttle which will overcome the above named disadvantages inherent in a wood shuttle and at the same time retain the advantages incident to forming the body of the shuttle from wood and particularly the advantages of having the sides of the shuttle of wood.

A further purpose of my invention is to provide a shuttle having sides of wood, but its upper and also preferably its lower surface of a hard, tough, grainless and practically frictionless fiber whereby the shuttle may be used for an indefinite time without roughening and without cutting the warp and at the same time will have its sides adapted to make the desired contact with the binders of the shuttle box.

A further purpose of my invention is to provide a loom shuttle of such construction that it will not require the use of expensive dog wood, but may use one of the several common hard woods.

A further purpose of my invention is to provide a loom shuttle of the general type outlined that will be provided with special features and combinations of parts peculiarly well adapted to meet the requirements.

Further purposes and advantages of my invention will appear from the specification and claims hereinafter set forth.

Fig. 1 is a perspective view of a loom shuttle embodying my invention.

Fig. 2 is a side elevation thereof.

Fig. 3 is a bottom plan view thereof.

5 Figs. 4, 5 and 6 are cross-sectional views on lines 4-4, 5-5 and 6-6 respectively of Fig. 1.

Referring to the drawings in a more particular description it will be seen that the 10 loom shuttle illustrated comprises a body 10 conveniently and preferably formed of wood and a top facing 11 and bottom facing 12 both of a hard, tough, grainless and practically frictionless fiber and the usual metal 15 end tips 13. The wood body 10 is the full width of the shuttle so that the wood of the body extends to and forms the sides 14 of the shuttle against which the binders and the backs of the shuttle boxes engage in the 20 usual reliable way to form a tight grip upon the shuttle without danger of the shuttle rebounding and without perceptible wear upon the shuttle. The body 10 is provided with the desired chamber 15 to receive the 25 bobbin (not shown). The wooden body also is provided with the usual means for supporting the spindle upon which the bobbin is to be placed. In the body are also placed the usual tension means not relevant to this 30 invention and so not further described.

The body 10 is of a thickness from top to bottom a little less than the thickness of the completed shuttle. Its opposite ends as at 35 16 also taper towards a point at about the curve or angle desired in the finished shuttle.

Upon the top and bottom respectively of 40 this wooden body are placed respectively the top facing 11 and bottom facing 12 composed of a strip or layer of hard, tough and grainless fiber adapted to pass by the warp and reed with a minimum amount of friction. 45 Preferably these surfacing strips will be shaped to substantially the shape of the top and bottom respectively of the completed shuttle before the strips are placed upon the wood body and are trimmed down and smoothed and finished off to the proper exact shape and smoothness of surface after the surfacing strips are on the shuttle.

50 The said surfacing strips will be securely and permanently secured to the wooden body of the shuttle as by strong glue or other adhesive applied to the contacting surfaces and the parts firmly held together until set.

55 Preferably also dowel pins 17 will be used especially along the central part of the side edges of the top facing strip 11 where the material of said strip is adjacent to the chamber 15 of the shuttle and so very narrow. In this way these narrow portions of the facing strips are further strengthened 60 against side strain. Preferably also rivets or other headed metallic members 18 will extend through both facing strips and the

65 wooden body at the nose or near the outer

ends of the shuttle and spaced only a short distance back from the head of the metal tip 13. By this means the extremities of the surfacing strips are held firmly to the wooden body at the point where they have 70 been bent down most to conform to the slope of the ends of the shuttle. As shown in Fig. 6 the rivet 18 may extend through an opening provided in the tang 19 of the metal tip thus serving as further means of holding 75 the metal tips to the shuttle.

The facing strips 11 and 12 it will be noticed thoroughly cover the top and bottom respectively of the shuttle and extend to the corners or side edges of the top and bottom and thus form the surface which comes into contact with the warp at the varying positions of the shed. It will thus be seen that the facing strips for the entire distance from the metal end tips form the 80 only surface coming into contact with the warp. Near the ends of the shuttle as shown in Fig. 6 the fiber facing strips are shaped to the usual almost round shape of this part of the shuttle, but still extend far enough 85 to the sides to form the contacting surface at this point. Farther from the ends of the shuttle as shown in cross sectional view in Fig. 5 the edges of the fiber facing strips form the corners of the shuttle and are 90 slightly rounded in the usual way, but still take all the wear from the warp. Through the central portion of the shuttle as shown in Fig. 4 the facing strips come to the four 95 corners of the shuttle with only a trifling rounding of the corner. It will thus be seen that no part of the wood of the shuttle is 100 exposed to the roughening or splintering action by contact with the warp, but that the said fiber facing strips form a complete and 105 the only contact with the warp aside from the light contact that may be made by the metal end tips in the usual way.

The strips of fiber used will be of sufficient thickness to obtain the necessary 110 strength, rigidity and durability. I find from experience, however, that the fiber even after long use shows no trace whatever of wearing rough or splintering. Therefore the layers do not need to be thick as there is 115 no occasion for continual trimming or smoothing down as is the case with wooden shuttles.

The fiber top and bottom facing strips being relatively thin do not extend far enough 120 down on the sides of the shuttles to prevent the wooden sides 14 being the only part of the shuttle that will come into contact with the metal binders of the shuttle boxes and the backs of the shuttle boxes. In this way 125 my shuttle has all of the advantages of firm and reliable contact with the binders in the shuttle boxes and the backs of the shuttle boxes incident to an all-wood shuttle.

As there is no tendency whatever for the 130

fiber of the facing strips to roughen or splinter from contact with the warp it will be seen that the operator can keep a set of shuttles in use indefinitely without having to change to

- 5 repair or replace and without the loss of time incident to watching wooden shuttles. As the splintering of the wood of the shuttle in contact with the warp has been the main cause of shuttles wearing out and being dis-
 10 carded it will be seen that my shuttle will last a long time instead of being very short-lived as has been the case with wooden shuttles. This will obviously tend to economy in weaving in that the shuttle may last for
 15 15 years instead of only for months or possibly only for a week or two.

Furthermore a shuttle embodying my invention may have its wooden body formed of any one of several common hard woods
 20 which will answer satisfactorily to form the body and the wood contact at the sides of the shuttle. The expensive dog wood is no longer required as the wood does not form any part of the surface which comes in contact with the warp.

The fiber used for the top and bottom facing strips may be any of the well-known compounds or compositions generally known in the trade as fiber or vulcanized fiber that
 30 are sufficiently hard, tough, durable and particularly grainless to answer the purpose in hand.

What I claim as new and desire to secure by Letters Patent is:

35 1. A loom shuttle having wooden sides of sufficient uninterrupted height to be the only parts engaged by the binders or by the opposite part of the backs of the shuttle boxes

and having its top faced with a layer of hard, tough, grainless fiber extending to the 40 sides and forming the upper edges of the shuttle.

2. A loom shuttle having wooden sides of sufficient continuous height to be the only parts engaged by the binders or by the opposite 45 part of the backs of the shuttle boxes and having its top and bottom faced with a layer of hard, tough, grainless fiber extending to the sides and forming the four edges of the shuttle.

3. A loom shuttle having a one-piece wooden body forming the opposite sides thereof and having its top faced with a layer of hard, tough, grainless fiber, said wooden sides being of sufficient uninterrupted height 55 to be the only parts engaged by the binders or by the opposite part of the backs of the shuttle boxes.

4. A loom shuttle having a continuous wooden body forming the opposite sides 60 thereof and having its top and bottom faced with layers of hard, tough, grainless fiber, said wooden sides being of sufficient height to be the only parts engaged by the binders or by the opposite part of the backs of the 65 shuttle boxes.

5. A loom shuttle having a front wooden side of sufficient continuous height to be the only part engaged by the binders and having its top and bottom faced with a layer of 70 hard, tough, grainless fiber extending to the sides and forming the four edges of the shuttle.

In witness whereof I have affixed my signature, this 28th day of June 1918.

CLARENCE K. SUYDAM.
